UNITED STATES PATENT OFFICE.

FRANK L. SIMMONS, OF WOONSOCKET, RHODE ISLAND, ASSIGNOR TO THE TAFT-PEIRCE MANUFACTURING COMPANY, OF WOONSOCKET, RHODE ISLAND, A CORPORATION OF RHODE ISLAND.

MAGNETIC CHUCK.

Application filed June 7, 1919. Serial No. 302,560.

To all whom it may concern:

Be it known that I, FRANK L. SIMMONS, a citizen of the United States, residing at Woonsocket, in the county of Providence, State of Rhode Island, have invented certain new and useful Improvements in Magnetic Chucks, of which the following is a specification.

This invention relates broadly to electrical apparatus and more specifically to magnetic chucks and the like.

The principal object of the present invention is to provide a magnetic chuck adapted more especially for work requiring a universal chuck.

Another object of the present invention is a magnetic chuck of the character specified and wherein the poles on the chuck are arranged to be especially applicable to holding work supported by built-up supports.

Another object of the present invention is a chuck of the character specified having a substantially rectangular work face portion with certain pole pieces arranged longitudinally thereof and certain other of the pole pieces arranged transversely thereof, whereby the face plate is adapted to hold work of various characters.

Another and principal object of the present invention is a face plate having the pole pieces thereof magnetically insulated one from another by a phenol condensation product and with reinforcing ribs or members adapted to support the said insulation between the pole pieces.

More specifically an object of the present invention comprises a face plate having a plurality of pole pieces separated one from another by non-magnetic members of bakelite, condensite, or the like, and with framing ribs of the face plate constructed to support the said non-magnetic insulating members.

Another and important object of the present invention is a magnetic chuck having a plurality of work face pole pieces and with an adjustable back strip arranged adjacent one edge of the work face and parallel to certain of said pole pieces, and with the said back strip being adjustable vertically and horizontally whereby an adjustable abutment is provided for setting the work on the pole pieces of the face of the chuck.

Another important object of the present

invention is a magnetic chuck of the character specified having an aluminum body and frame provided with a terminal box having a cast aluminum cap adapted to be seated with a water-tight joint against the face of the body of the chuck for wet grinding.

The present invention possesses many other advantageous features some of which, together with the foregoing, will be set out more at length in the following description wherein will be outlined in full that form of the invention which I have selected for illustration in the drawings accompanying and forming a part of this specification.

In the drawings I have shown only one specific form of my generic invention, but it is to be understood that I do not limit myself to such form because my invention may be embodied in a multiplicity of forms, each being a species of my invention. It is also to be understood that by the claims succeeding the description of my invention I desire to cover the invention in whatsoever form it may be embodied.

Reference will now be made to the drawings wherein like characters are used to represent like parts throughout the several figures thereof.

Figure 1 is a plan view of one embodiment of my invention with the back strip and supporting bolts therefor removed.

Figure 2 is an elevational view of the device shown in Figure 1 and with one-half of the device shown in longitudinal section.

Figure 3 is an end view of the device showing the back strip in place and showing a section of the face plate taken on line A—A of Figure 2.

Figure 4 is a detail of a portion of the adjustment mechanism for adjusting the back strip horizontally.

Figure 5 is a detail view showing the adjustment mechanism for the back strip.

Figure 6 is a plan view of the terminal block showing a portion of the block in section.

Figure 7 is a longitudinal section of the terminal block showing the same in position on the side wall of the body portion of the chuck.

Heretofore in the art of rectangular magnetic chucks it has been customary to arrange the pole pieces transversely of the

face of the chuck since this arrangement gives greater holding power for holding flat pieces extending longitudinally of the chuck.

5 In the majority of cases rectangular chucks are used on machine tools with the length of the chuck parallel to the length of the bed of the tools so that the displacement forces acting on the work are in most 10 cases lengthwise of the chuck and it is desirable to obtain the greatest holding power against such forces.

It frequently becomes desirable, particularly in a small shop, to build up supports 15 for work by using parallels and then laying the work upon the parallels. To facilitate this it is desirable that the pole pieces be variously arranged, and for a rectangular chuck one of the most convenient 20 arrangements comprises arranging certain pole pieces transversely of the chuck face and other pole pieces longitudinally. It is also possible to build up work upon groups of longitudinally extending pole pieces whereby exceedingly strong magnetic fields between the built-up members are obtained.

Heretofore in the art of magnetic chucks it has been customary to utilize Babbitt 25 metal or other soft metal as non-magnetic fillers between the pole pieces. This soft metal tends to wear away and therefore leaves the face uneven; it also tends to hold particles of emery or carborundum so that 30 they scratch or mar fine work. In the present case the objections to such material are overcome by using a phenol condensation product, for example, condensite or the like.

35 The spacing members between the poles are supported by ribs which comprise a portion of the face plate frame so that a substantial grid of supporting metal is provided by the face plate frame. Preferably 40 the face plate frame is of non-magnetic metal, such as aluminum, and therefore no magnetism is lost by short-circuiting due to the ribs or grid members extending between the pole pieces.

45 Magnetic chucks are frequently used for wet grinding and waterproofing becomes more or less of a problem. The present invention comprises a thoroughly waterproof housing for the cores by providing 50 a strip of tin or brass which extends over the tops of the pole pieces and beneath the face plate, and by further providing an aluminum cap box for the terminal block. The aluminum cap box has sufficient 55 strength to permit it to be firmly or securely seated against the side of the body of the chuck and provides a water-tight joint at this juncture.

55 Referring now to the drawings, the chuck comprises a housing 1 which preferably is

an open box having integral sides and bottom, and in the preferred form is made of aluminum. This housing or body is provided with lifts 2 which are adapted to carry the core casting 4. This core casting 70 4 preferably is of special magnet steel and is provided with a base 5 that carries a plurality of core pole pieces 6 which are substantially flat plate-like members extending upwardly, and preferably integral with the 75 base. These core pole pieces are arranged in groups to correspond to the arrangement of the face plate pole pieces which will later be described. Each core pole piece carries an individual magnetizing coil 7 80 whereby the pole pieces are suitably energized. The upper ends of the core pole pieces and the upper edges of the housing or body are ground to lie in a common plane thereby insuring a good contact with the 85 work face pole pieces. Preferably a waterproofing sheet 8 is arranged over the upper ends of the core pole pieces and extends over the edges of the sides thereby forming a complete cover for the pole pieces and 90 coils. This sheet is of thin material, but is shown in the drawings in exaggerated thickness to more clearly illustrate the same.

A face plate is adapted to be supported on the core pieces and the sides of the housing. 95 This face plate comprises a frame 9 in which the face plate pole pieces are maintained. Certain of the face plate pole pieces 10 extend transversely of the face plate and certain other of the face plate pole pieces 11 100 extend longitudinally of the face plate. Transverse ribs 12 extend across the face plate frame and between the underportion of certain of the face plate pole pieces. Longitudinally extending ribs 14 likewise extend 105 between certain other of the face plate pole pieces. The ribs 14 together with the ribs 12 and the face plate frame comprise a grid in which the face plate pole pieces set. Preferably this grid is made of non-magnetic 110 metal which in the preferred form is aluminum. By making this grid of non-magnetic metal the danger of short-circuiting pole pieces by means of the ribs 12 and 14 is obviated.

115 The spaces between the face plate pole pieces are preferably filled with bakelite, condensite, or other hard phenol composition, and comprise insulating spacers 15. Both the upper and lower surfaces of the 120 face plate comprise plane surfaces and preferably these are parallel. A plurality of through bolts 16 extend upwardly through suitable openings in the sides of the housing and through openings in the waterproofing 125 sheet 8, and are threaded or tapped into the face plate frame, whereby the face plate is tightly clamped in position on the housing.

130 It is desirable to provide a detachable terminal block in order to facilitate the com-

pling of the electrical connections, and a preferred form of terminal block is illustrated in Figures 6 and 7. The terminal wires from the coils 7 are brought through 5 openings 17 in the block base 18 and are clamped by the binding screws 19. This terminal block base 18 preferably is a molded bakelite or condensite member and is firmly seated against the side of the housing 1 by 10 machine screws 20. A cover cap comprising an aluminum casting 21 is provided with a terminal conduit member 22 and is constructed with upstanding lugs 24 that carry an insulating fiber plate 25 which is secured 15 in position on the lugs by means of the stub screws 26. This fiber plate carries a pair of terminal spring fingers 27 and 28 which are adapted to be connected with the lead wires through which electrical energy is to be supplied. This cover cap 21 is held in position 20 against the chuck body by stub screws 29 and preferably a water-tight gasket or packing 30 of suitable material such as that known under the trade name of "vellumoid" 25 is provided between the edges of the cover cap 21 and the side wall of the body 1. The positioning of the cap against the side of the body automatically brings the terminal fingers 27 and 28 into engagement with the 30 binding screws 19 so that when the cap is in position the electric circuit with the feed cable is completed. A water shed 31 also prevents a certain amount of water from reaching the cover cap and further assists 35 the waterproofing.

In a chuck of this character it is particularly desirable that a universally adjustable back plate be provided as the operation of the back plate is thereby facilitated by providing for horizontal as well as vertical adjustments. This back plate is illustrated in 40 Figures 3, 4, and 5, and comprises a rest support 32 which has bifurcated arms 34 that are adapted to extend over stub bolts 45 35 and to be clamped in predetermined vertical adjusted positions by means of the said stub bolts. The upper portion of the rest support is grooved as at 36 to provide guide-ways for the guide blocks 37 which are secured to the under portion of the back strip 38 and guide the longitudinal movements 50 of the strip. Adjustment screws 39 are set in the rest support 32 and the heads of these screws engage recesses 40 in the back strip 38 so that by turning these adjustment screws the back strip may be moved over the chuck face. When a predetermined adjustment has been made, the back strip 55 may be clamped in adjusted position by the screws 41 and 42 which cause the guide blocks to be clamped against the upper portions of the grooves 36. It is important 60 that this back plate shall be non-magnetized, otherwise work which has been released 65 from the chuck may stick to the back plate

thereby requiring special care in removing the work. Where the back plate is magnetized, the unexpected holding power has been the cause of workmen dropping work, thereby injuring both the work and the 70 chuck. In the construction herein illustrated the non-magnetic character of the back plate is secured by mounting the rest support 32 for the plate upon and against the non-magnetized housing 1. 75

From the foregoing it will be noted that the chuck comprising the present invention, because of the arrangement of the face plate pole pieces, is particularly adapted for use on a multitude of different types of work, 80 and is particularly useful in small shops which use a magnetic chuck for a plurality of purposes. 85

Having thus described my invention, what I claim is:

1. In a magnetic chuck or the like, the combination of a housing, electro-magnetic energizing means within said housing, a face plate covering said housing, said face plate comprising a frame and individual pole pieces within said frame, said pole pieces having undercut portions, non-magnetic material separating said pole pieces one from another, and reinforcing means extending through said non-magnetic material. 90
2. In a magnetic chuck or the like, the combination of a housing, electro-magnetic energizing means within said housing, a face plate covering said housing, said face plate comprising a frame and individual pole pieces within said frame, said pole pieces having undercut portions, a hard phenol condensation material separating said pole pieces one from another, and reinforcing means extending through said condensation material. 100
3. In a magnetic chuck or the like, the combination of a housing, electro-magnetic energizing means within said housing, a face plate covering said housing, said face plate comprising a frame and individual pole pieces within said frame, said pole pieces having undercut portions, non-magnetic material separating said pole pieces one from another, and reinforcing ribs extending through said non-magnetic material, and beneath said pole pieces. 110
4. In a magnetic chuck or the like, the combination of a housing, electro-magnetic energizing means within said housing, a face plate covering said housing, said face plate comprising a frame and individual pole pieces within said frame, said pole pieces having undercut portions, non-magnetic material separating said pole pieces one from another, and reinforcing ribs extending through said non-magnetic material, said ribs and said frame being integral. 120
5. In a magnetic chuck or the like, the combination of a housing, electro-magnetic 130

- means within said housing, a face plate covering said housing, said face plate comprising a frame of non-magnetic material and individual pole pieces within said frame, said pole pieces having undercut portions, non-magnetic material separating said pole pieces one from another, and reinforcing ribs of non-magnetic material extending through said non-magnetic material.
6. In a magnetic chuck or the like, the combination of a housing, electro-magnetic energizing means within said housing, a face plate covering said housing, said face plate comprising a frame of non-magnetic material and individual pole pieces within said frame, said pole pieces having undercut portions, a hard phenol condensation member separating said pole pieces one from another, and reinforcing ribs of non-magnetic material extending through said condensation material, said ribs and said frame being integral.
7. A magnetic chuck and the like comprising a housing, electro-magnetic energizing means within said housing, a face plate covering said housing, said face plate comprising a plurality of individual pole pieces, a frame within which said pole pieces are mounted, in combination with a back strip so placed as to be magnetically unaffected by said energizing means and adapted to comprise an abutment against which work may be set over said plate, means whereby said back plate may be adjusted transversely of the face plate, and means to lock the back strip in adjusted positions.
8. A magnetic chuck and the like comprising a housing, electro-magnetic energizing means within said housing, a substantially rectangular face plate covering said housing, said face plate comprising a plurality of substantially rectangular individual pole pieces, and a frame within which said pole pieces are mounted, in combination with a back strip so placed as to be magnetically unaffected by said energizing means and having an edge substantially parallel to certain of the pole pieces and adapted to comprise an abutment against which work may be set over said face plate, and means whereby said back plate may be adjusted transversely of said face plate.
9. A magnetic chuck and the like comprising a housing provided with an opening in a wall thereof, electro-magnetic energizing means within said housing, a face plate covering said housing, said face plate comprising a frame and a plurality of pole pieces supported within said frame, a waterproofing sheet beneath said face plate and covering said housing, and a waterproof terminal box mounted over said opening and secured to one side wall of said housing by means of a waterproof joint whereby moisture is excluded from the interior of said housing.
10. A magnetic chuck and the like comprising an aluminum housing having an opening in one side wall thereof, electro-magnetic energizing means within said housing, a face plate comprising an aluminum frame and a plurality of pole pieces supported within said frame, a waterproofing sheet beneath said face plate and covering said housing, and an aluminum waterproof terminal box mounted over said opening and secured to one side wall of said housing by means of a waterproof joint whereby moisture is excluded from the interior of said housing.
11. A magnetic chuck and the like comprising a housing, electromagnetic means within said housing, a plurality of upright pole pieces in operative relation to said electromagnetic means, said pole pieces being substantially rectangular in cross-section, certain of said pole pieces being disposed at right angles to others thereof, and a substantially rectangular face plate covering said housing, said face plate comprising a plurality of face plate pole pieces substantially rectangular in cross-section mounted directly above said rectangular pole pieces with each of said face plate pole pieces disposed in a direction corresponding to the direction of its respective pole pieces.
12. A magnetic chuck and the like comprising a housing, electromagnetic means within said housing, a separate frame having substantially a rectangular opening therein, a plurality of independent pole pieces in said housing, substantially rectangular face plate pole pieces mounted in said frame above said pole pieces, a plurality of longitudinal and transverse ribs forming a grid in which said pole pieces set and non-magnetic means separating all of said pole pieces from each other and from said frame.
13. A magnetic chuck and the like comprising electro-magnetic means within said housing, a plurality of up-right pole pieces in operative relation to said magnetic means, a substantially rectangular face plate covering said housing, said face plate comprising substantially rectangular face plate pole pieces, a frame within which said pole pieces are mounted, certain of said pole pieces extending transversely of said face plate and others extending longitudinally thereof, and non-magnetic material holding said pole pieces separated from each other and from said frame.

FRANK L. SIMMONS.
